D15-73. OR D13,876 EX

DESIGN FOR ORNAMENTATION OF SEWING-MACHINES.

Design No. 13,876, dated May 1, 1883.

Fig. 2.

UNITED STATES PATENT OFFICE.

WILLIAM HAEHNEL, OF NEW YORK, N. Y., ASSIGNOR TO CHARLES PALM
AND JULIUS FECHTELER, OF SAME PLACE.

DESIGN FOR ORNAMENTATION OF SEWING-MACHINES.

SPECIFICATION forming part of Design No. 13,876, dated May 1, 1883.

Application filed March 24, 1883. Term of patent 7 years.

To all whom it may concern:

Be it known that I, WILLIAM HAEHNEL, of New York, county and State of New York, have invented a new and original Design for 5 Ornamentation of Sewing-Machines, of which the following is a specification.

This invention relates to a new and original design for the ornamentation of sewing-machines and other articles; and it consists in 10 the novel grouping and configuration of figures hereinafter more fully described.

The accompanying illustrations show in Figures 1 and 2 opposite views of a sewing-machine plate and arm having thereon my new 15 design. Figs. 3 and 4 are enlarged detail views of the ornamentation at the sides of the cloth-plate. Fig. 5 is an enlarged detail view of the ornamentation at the front portion of the cloth-plate. Figs. 6, 7, and 8 are enlarged de- 20 tail views of the ornamentation of the various sides of the post of the sewing-machine arm. Fig. 9 is an enlarged detail view of the ornamentation at the side of the sewing-machine arm. Fig. 10 is an enlarged detail view of 25 the ornamentation at the top of the arm.

The figure A, which ornaments the front of the cloth-plate, consists of slender intertwining tendrils apparently starting from a common center, and bearing pointed leaves.

The figures B B, which ornament the sides 30 of the cloth-plate, consist of long curving sprays bearing pointed leaves and intertwining tendrils in large numbers.

The figure D, which ornaments that side of 35 the post supporting the sewing-machine arm shown in Fig. 1, consists of a figure in pyramidal shape, made up of twining tendrils bearing leaves similar to those already described.

The figure E, which ornaments the post supporting the sewing-machine arm at its bottom, on the side shown in Fig. 2, is a smaller triangular figure made up of similar twining tendrils and leaves; and the figure F, which 45 ornaments the base of the supporting-post on its inside, as shown in both Figs. 1 and 2, consists of a similar triangular-shaped figure made up of twining tendrils and pointed leaves.

The figure G, which ornaments both sides 50 of the sewing-machine arm, consists of ten-

drils bearing similar pointed leaves twined around the inscription "Davis," or other inscription, all placed against the side of the sewing-machine arm.

The figure H, which ornaments the top of 55 the sewing-machine arm, is composed of long slender twining tendrils bearing pointed leaves similar to those heretofore described.

I claim—

1. The design for the ornamentation of 60 sewing-machines, consisting of the figure A, substantially as shown.

2. The design for the ornamentation of 65 sewing-machines, consisting of the figure B, substantially as shown.

3. The design for the ornamentation of 70 sewing-machines, consisting of the figure D, substantially as shown.

4. The design for the ornamentation of 75 sewing-machines, consisting of the figure E, substantially as shown.

5. The design for the ornamentation of 80 sewing-machines, consisting of the figure F, substantially as shown.

6. The design for the ornamentation of 85 sewing-machines, consisting of the figure G, substantially as shown.

7. The design for the ornamentation of 90 sewing-machines, consisting of the figure H, substantially as shown.

8. The design for the ornamentation of 95 sewing-machines, consisting of the figures A and B, substantially as shown.

9. The design for the ornamentation of 100 sewing-machines, consisting of the figures D, E, and F, substantially as shown.

10. The design for the ornamentation of 105 sewing-machines, consisting of the figures G and H, substantially as shown.

11. The design for the ornamentation of 110 sewing-machines, consisting of the figures D, E, F, G, and H, substantially as shown.

12. The design for the ornamentation of 115 sewing-machines, consisting of the figures A, B, D, E, F, G, and H, substantially as shown.

WILLIAM HAEHNEL.
